UNITED STATES PATENT OFFICE.

RAFFAELE PIRO, OF NAPLES, ITALY.

SAFETY RAZOR WITH ROLLING BLADE.

Application filed November 13, 1923, Serial No. 674,570, and in Italy November 14, 1922.

This invention relates to safety razors of the type which are adapted to be adjusted so as to compensate for wear of the blade.

The object of the present invention is to provide an improved safety razor which is constructed so as to allow of adjustment to compensate for the wearing away as by grinding of substantially half of the razor blade.

10 A further object of the invention is to provide an improved construction of safety razor whereby the clamping members for the blade are adapted to be located in the same position relatively to the cutting edge 15 of the blade during all conditions of the blade within the limits of wear allowed for.

15 A further object of the invention is to provide an improved construction of safety razor adapted to allow of adjustment for compensating for the wearing away of substantially half the blade which is adapted to be used with blades of the flexible type.

With the foregoing and other objects in view, the invention consists in the details of 20 construction, and in the arrangement and combination of parts to be hereinafter more fully set forth and claimed.

In order that the invention may be clearly understood reference is made to the accompanying drawings which illustrate by way of example an embodiment of the invention and in which:—

Fig. 1 is an end elevation of my improved safety razor looking in the direction of the arrow indicated in Fig. 2.

Fig. 2 is a side elevation of my improved safety razor.

Figs. 3 and 4 are respectively end and rear elevations of the member adapted to clamp the blade in position.

Figs. 5 and 6 are respectively end and rear elevations of the serrated guard member.

Figs. 7 and 8 are respectively end and rear views of a member adapted to cooperate with the serrated guard member.

As illustrated in the drawings the safety razor comprises a hollow handle 1, through which extends an elongated screw threaded nut 2 having an enlarged end 2*, such nut being adapted to engage the screw threaded pin or the like 3 on the clamping member 4, this construction being substantially the same as in a Gillette razor.

The clamping member comprises a substantially narrow head 5 of a width preferably half that of the blade to be used with the holder, the screw threaded pin 3 extending from one side thereof and being located centrally thereof. Also extending from such member 5 on the same side as the screw threaded pin 3 are two lugs 6 arranged respectively on opposite sides of the pin 3. Such clamping member is adapted to clamp the blade 7 to the handle 1 between a serrated guard 8 and a cooperating member 9, such members and the blade being provided with perforations to accommodate the pin 3 and lugs 6 on the clamping member 4. The perforations in the blade are of circular formation and are of a size to engage with the screw threaded pin 3 and the lugs 6 without any play whereby when the clamping member 4 is secured to the handle 1 the blade 7 will be immovable relatively thereto.

The perforations in the guard member 8 and the cooperating member 9 which are indicated respectively by reference numerals 10 and 11, are elongated, the elongation being in a direction transversely of such members whereby said members prior to the tightening of the clamping member 4 may be moved relatively thereto in a direction transversely of the blade. The guard member 8 and the cooperating member 9 are preferably connected together so as to prevent relative movement therebetween in a direction transversely of the blade by means of lugs 12 mounted on extensions 13, 13 respectively extending from the two side edges of the member 9, such lugs 12, 12 being adapted to engage in perforations 14, 14 located in extensions 15, 15 on the side edges of the guard member 8.

The forward edge of the cooperating member 9, namely, the edge cooperating with the cutting edge of the razor blade 7 is provided at the ends thereof with two extensions 16, 16 which are bent at right angles 100 as shown in Figure 7 of the drawings, such extensions being adapted to engage with the outer teeth 17, 17 of the corresponding serrated edge of the guard member 8. The outer teeth 17 are preferably of a depth 105 somewhat less than that of the remaining teeth 18 of the serrated edge, the reduction in depth being such as will accommodate

the extensions 16, 16 so that the same do not extend beyond the outer edges of the teeth 18.

5 The guard member 8 as clearly shown in the drawings is curved, the surface 19 thereof remote from the handle 1 being convex. The surface 20 of the cooperating member 9 which cooperates with the convex surface 19 is concave to an extent corresponding to the 10 convexity of the surface 19. The blade 7 is normally flat but is made of resilient steel so that it can readily be bent into a curved formation when it is clamped between the members 8 and 9.

15 In assembling the razor the guard member 8 is located at the end of the handle 1 and the razor blade 7 is located between the guard member and the cooperating member 9. The position of the razor blade will be 20 fixed as soon as the lugs 6 on the clamping member 4 engage within the perforations thereof and the adjustment of the razor is effected by moving the members 8 and 9 transversely of the blade 7 prior to the 25 tightening down of the clamping member. Correct adjustment is obtained when the inner sides of the extensions 16, 16 engage the cutting edge of the razor blade 7.

By such a construction as described it will 30 be readily appreciated that the relative positions of the forward edges of the member 9, the guard member 8 and the blade 7, will always be the same no matter to what extent the width of the razor blade has been reduced by sharpening. Owing to the fact that the head 5 of the clamping member is of a 35 relatively narrow width considerable latitude is allowed for the adjustment of the members 8 and 9 and thus allowance is made 40 for a considerable reduction in the width of the blade 7. When one side of the blade 7 has been ground down to such an extent that the cutting edge thereof does not project 45 beyond the head 5 the blade may be reversed and the opposite edge thereof used as a cutting edge.

What I claim is:

1. A safety razor comprising in combination 50 a handle, a guard member and a cooperating member adapted to clamp therebetween a resilient blade, and means for maintaining said clamping members in clamping position on said handle and for preventing movement of said blade relatively to said handle, said guard member and the cooperating member being adapted to be adjusted transversely of the blade whereby the blade 55 may always be gripped by said clamping members in the same relatively position with respect to the cutting edge thereof, notwithstanding reduction in width of the blade due to sharpening.

60 2. A safety razor as claimed in claim 1, in

which means are provided for preventing relative movement between the guard member and the cooperating member.

65 3. A safety razor comprising in combination a handle, a guard member and a cooperating member, adapted to clamp a resilient blade therebetween and to grip such 70 blade adjacent the cutting edge thereof, and a member extending longitudinally of the blade and of a width comparatively slight with respect to that of the cooperating 75 clamping member, such longitudinally extending member being adapted to maintain said clamping members in clamping position on said handle and to prevent movement of said blade relatively to said handle, said guard member and the cooperating member 80 being adapted to be adjusted transversely of the blade, whereby the blade may always be gripped by said clamping members in the same relative position with respect to the cutting edge thereof, notwithstanding the 85 reduction in width of the blade due to sharpening.

90 4. A safety razor comprising in combination a handle, a guard member having a curved upper face, a member having a surface conforming with the curved upper face of the guard member adapted to cooperate with said guard member to clamp a resilient 95 blade against said upper face, and means for maintaining said clamping members in clamping position on said handle and for preventing movement of said blade relatively to said handle, said guard member and the cooperating member being adapted to be adjusted transversely of the blade whereby 100 the blade may always be gripped by said clamping members in the same relative position with respect to the cutting edge thereof, notwithstanding reduction in width of the blade due to sharpening.

105 5. A safety razor comprising in combination a handle, a guard member and a cooperating member adapted to clamp therebetween a resilient blade, means for maintaining said clamping members in clamping position on said handle and for preventing movement of said blade relatively to said handle, said guard member and the cooperating member being adapted to be adjusted transversely of the blade whereby the blade 110 may always be gripped by said clamping members in the same relative position with respect to the cutting edge thereof, notwithstanding reduction in width of the blade due to sharpening, and means for correctly positioning said clamping members relatively 115 to the cutting edge of the blade.

120 In testimony whereof I hereunto affix my signature.

RAFFAELE PIRO.
